US00D828334S

(12) **United States Design Patent** (10) Patent No.: **US D828,334 S**
(45) Date of Patent: **** Sep. 11, 2018**

(54) **DIGITAL AUDIO PLAYER WITH
COMMUNICATION AND MIXING
FUNCTION**

(71) Applicant: **Pioneer DJ CORPORATION**,
Yokohama-shi, Kanagawa (JP)

(72) Inventor: **Jinta Kobayashi**, Tokyo (JP)

(73) Assignee: **Pioneer DJ CORPORATION**,
Yokohama-shi, Kanagawa (JP)

(**) Term: **15 Years**

(21) Appl. No.: **29/610,244**

(22) Filed: **Jul. 11, 2017**

(30) **Foreign Application Priority Data**

May 17, 2017 (JP) 2017-010518

(57) **CLAIM**

I claim the ornamental design for a digital audio player with
communication and mixing function, as shown and
described.

DESCRIPTION

FIG. 1 is an upper-right-front perspective view showing the
design;

FIG. 2 is a lower-left-back perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

1 Claim, 8 Drawing Sheets
